ELECTRIC ERASER

John Robinson, Dallas, Tex.

Application July 20, 1956, Serial No. 42,326

Term of patent 14 years

(Cl. D74—7)

I claim:

The ornamental design for an electric eraser, substantially as shown.
